(57) **CLAIM**

We claim the ornamental design for an intelligent peripheral device, as shown and described.

DESCRIPTION

FIG. 1 is an isometric front top-side perspective view showing our new design;

FIG. 2 is a top view thereof;

FIG. 3 is a bottom view thereof;

FIG. 4 is a front view thereof;

FIG. 5 is a back view thereof;

FIG. 6 is a right side view thereof; and,

FIG. 7 is a left side view thereof.

The broken line showings are included for the purpose of illustrating unclaimed portions of the intelligent peripheral device and form no part of the claimed design.
